UNITED STATES PATENT OFFICE.

PHILIP S. HARPER, OF CHICAGO, ILLINOIS.

GAS BURNER.

Application filed April 10, 1922. Serial No. 551,011.

My invention relates to sectional gas burners and particularly to atmospheric burners of the open top type used for cooking purposes with a grid or grating there-
above upon which is placed the cooking ves-
sel to be heated.

My invention consists in separating the burner ports of the individual sections whereby immediate ignition of one sec-
tion from another is prevented, and in so
placing the said ports that the ignited and
unignited gas streams from one section and
another are brought together for ignition at
some certain greater distance from the open-
ings of the said ports.

I have discovered by experiment that in
a sectional open top burner having burner
ports in the upper side thereof that if the
said ports in one section are placed suf-
ficiently close to ports in the next section
for one section to ignite from the other
without a cooking vessel on the said grid,
then in igniting the sections one from the
other particularly with a vessel on the said
grid a flashback into the burner body will
occur unless the burner is being operated
at a very high velocity of mixture through
the burner ports, which expedient is not al-
ways possible nor desirable. This flashing
back is due to the fact that when gas is
first turned into a burner a very lean mix-
ture is discharged from the burner ports,
such mixture burning with great rapidity
and hence very readily flashing back
through the burner ports into the body of
the burner. It is known that if the ports
are spaced sufficiently apart so as to prevent
such firing back as described no interignition
without a vessel on the grid normally
takes place, but I have discovered that in
such case one section may successfully be
ignited from another by bringing the flame
or hot combustion products of the one into
mixture with the combustible gases of the
other at some certain distance from the
openings of the said burner ports. Success-
ful ignition is obtained in such event due to
the fact that when the combustible mixture
is sufficiently rich at this certain distance to
ignite, the mixture at that time actually
coming through the burner ports is so rich
and consequently slow burning, as to pre-
vent the firing back through the ports into
the burner.

It should be noted that in the case of
a closed top stove, satisfactory interlight-

ing of the sections can be obtained simply
by proper spacing of the ports, the im-
pinging and spreading of the combustion
gases under the said solid top causing in-
termixture and consequent ignition. My
invention relates only to the higher efficiency
open top or grid top burner where special
provision is necessary to cause the converg-
ing and intermixing of the gases from dif-
ferent sections at a certain distance from
the port openings such as necessary to ob-
tain satisfactory ignition of one section
from another under all conditions as herein
specified.

The principal object of this invention is
the provision of an open top sectional
burner in which, with no cooking vessel
on the grid thereof, one section may be
ignited from another, and at the same time
such a burner in which no firing back into
the burner body will occur under any nor-
mal operating conditions.

A further object of this invention is the
provision of a sectional burner with a grid
suitable and satisfactory for all sizes of
cooking vessels adapted for use in connec-
tion with a burner of the said type.

These and other objects of my invention
will be more apparent and better understood
by reference to the drawings, in which—

Figure 1 is a plan view of a two section
burner of the preferred form of my inven-
tion;

Figure 2 is a sectional elevation along
the line 2—2 of the burner shown in Fig-
ure 1;

Referring now specifically to the draw-
ings, a burner body 10 is shown having
openings 11 and 12 into one or both of
which with any suitable control means a
mixture of gas and air may be injected, the
said openings 11 and 12 connecting respec-
tively to burner sections 13 and 14, said sec-
tions lying in a horizontal plane and being
concentrically positioned as shown. Each
of the said sections 13 and 14 has a plural-
ity of burner ports as 15, 16, 17 and 18 ex-
tending through the upper sides thereof,
the ports 18 in the section 14 being at a con-
siderable distance from the nearest ports 17
in the section 13 such distance being pro-
vided for the purposes herein specified.
The outer ports 15 in section 13 are placed
circumferentially of the burner body 10 in
place of continuing in radial lines as in the
ordinary burner of this type, such improved

arrangement permitting provision of the necessary space between the ports of different sections without increasing the total diameter of the burner. Above the said burner sections supported in any practical manner at a suitable distance therefrom is a grid member 19 with radial prongs 20 which in this form of my invention are joined to a center ring 21 which is cut at points 22 in sections in order to provide for expansion and contraction on heating. The said ring 21 is so placed as to partially cover as shown the burner ports 17 in the outer section 13 so that jets of combustible mixture from the 15 said ports are spread out on impinging against the said ring in the said grid 19, part of the said mixture being deflected toward and over the ports 18 of the inner section 14 whereby, with the said inner section 20 burning, when fuel is turned into the outer section it will be ignited in due course without firing back into the burner body, all in accordance with causes hereinbefore disclosed. The stack effect of the hot products 25 of combustion from the inner section in passing through the said ring portion 21 also have a tendency to cause a similar flow of the combustible mixture from the outer section, such factor contributing materially 30 in the result.

While I have described more or less precisely the details of construction, I do not wish to be understood as limiting myself thereto, as I contemplate changes in form 35 and the proportion of parts and the substitution of equivalents as circumstances may suggest or render expedient without departing from the spirit or scope of my invention.

40 I claim:—

1. An open top gas stove burner having two substantially horizontal sections, each of said sections having a fuel supply passage thereto, each of said sections having a 45 plurality of burner ports in the upper side thereof, the ports in one section being spaced apart from the corresponding ports in the other section so that in normal combustion of gas passing therefrom the gas will not be ignited by the flame from an adjacent section, and means for impinging the gas from the said ports of one section towards the said ports of the other section.

55 2. A plurality of gas burner sections, each section having a fuel supply passage connected thereto, each of said sections also having a plurality of burner ports in the upper side thereof, the ports in one section being spaced from the corresponding ports in the other section a distance greater than the minimum spacing between ports in any 60 one section so that in normal combustion of gas passing therefrom the gas will not be ignited by the flame from an adjacent section, and means for diverting the flow from

the said ports of one section to the said ports of the other section.

3. A plurality of gas burner sections, each section having a fuel supply passage connected thereto, each section also having a 70 plurality of burner ports in the upper side thereof, the ports in one section being spaced from the corresponding ports in the other section at a distance greater than the minimum spacing of ports in any one section so 75 that in normal combustion of gas passing therefrom the gas will not be ignited by the flame from an adjacent section, and deflecting means directly in line with the said ports in one section and extending towards 80 the said ports in another section.

4. In an open top gas stove burner a burner body member having two substantially horizontal concentric sections, each of the 85 said sections having a fuel supply passage thereto, each of the said sections having a plurality of burner ports in the upper side thereof, the said ports in one section being spaced apart from the said ports in another section a greater distance than the minimum 90 spacing of the said ports in the same section; a grid member supported above the said sections whereon a cooking vessel may be placed for heating, the said grid member having a ring shaped portion extending over 95 the jets of one section and towards the jets of the other section.

5. In an open top gas stove burner a burner body member having two substantially horizontal concentric burner sections, each 100 of the said sections having a fuel supply passage thereto, each of the said sections having a plurality of burner ports in the upper side thereof, the said ports in one section being spaced apart from the said ports in another section a greater distance than the minimum spacing of ports in the same section, and in the outer of the said sections the said ports being positioned so that rows 105 of ports extend both radially and circumferentially in any group of ports having substantially the minimum port spacing; a grid member supported above the said sections whereon a cooking vessel may be placed for heating, the said grid member having a ring shaped portion extending over 110 the jets of one section and towards the jets of the other section.

6. In combination a burner body having 115 a plurality of burner sections concentrically arranged with respect to each other, each burner section having rows of concentrically arranged burner ports therein, the row of one section being spaced apart from the row of the adjacent section so that in normal 120 combustion of gas passing therefrom the gas will not be ignited by the flame from another section, and means whereby the gas from one section is impinged toward the 125 other section.

7. A gas burner having two heating sections arranged within the area covered by the usual cooking vessel, each section having a fuel supply thereto and a plurality of 5 burner ports in the upper side thereof, the ports of one section being spaced apart from those in another section, a distance greater than the maximum port spacing in either section, a grid member supported

above the said sections whereon a cooking vessel may be placed for heating, the said grid having a solid portion substantially extending over the space between the burner ports of the said two burner sections.

Signed at Chicago, Illinois, this 3rd day of April, 1922.

PHILIP S. HARPER.
